TABLE

Hugh J. Sloan, Waynesville, N. C., assignor to
William S. Sloan, Wilson, N. C.

Application November 18, 1937, Serial No. 175,313

3 Claims. (Cl. 311—103)

This invention relates to improvements in tables, it being a particular purpose to so improve bridge tables as to enable the simultaneous opening of all of the legs, without having to turn the table from side to side and open each leg individually. It is common knowledge that the latter practice prevails and the troublesome feature lies in the probability of swinging the various legs into the path of furniture, thus obstructing the motion, or swinging the leg against some person.

It is readily understood that when the operation of individually opening each of the four legs of a bridge table is multiplied by two or three and often more tables, considerable annoyance arises from the loss of time thus represented. With the initially stated purpose in mind, the objects of the invention are as follows:

First, to so locate the leg-opening mechanism 20 of the table that it forms a brace for the legs in a plane below the table top, and to supplement said bracing leg-opening mechanism with a locking bar which holds said mechanism rigid until released by hand.

Second, to provide a turnable leg-opening mechanism which is held at the limit of its opening movement by a locking bar which holds said mechanism under a degree of tension, thus causing the latter to exercise the previously mentioned bracing function.

Third, to provide a falling and rising tray as a supplement to the bridge table and to the leg-opening mechanism thereof, said tray being attached to said leg-opening mechanism so that it automatically lowers into a useable position when said mechanism opens the legs, and automatically raises to a nested position close to the nether side of the table top when said mechanism is employed to close the legs.

Fourth, to provide a hinge coupling which is centrally secured beneath the table top and has the central spider swiveled to it for the purpose of producing uniform opening and closing movements and to guard against any binding in the leg-opening mechanism because of the centralization of the spider.

Other objects and advantages will appear in the following specification, reference being had to the accompanying drawings in which:

Figure 1 is a perspective view from beneath the improved table, showing the legs in the open position.

Figure 2 is a fractional section taken on the line 2—2 of Fig. 1.

Figure 3 is a detailed perspective view of a

portion of one of the legs and an adjacent link, particularly illustrating the swivel connection.

Figure 4 is a detail perspective view particularly illustrating the spring hinge of the locking bar.

Figure 5 is an inverted plan view of the table showing the legs in the closed position.

Figure 6 is a cross section taken on the line 6—6 of Fig. 5.

Figure 7 is a cross section taken on the line 10 1—1 of Figure 6.

Figure 8 is a detail sectional view of the hinge coupling, particularly showing its swivel connection to the central spider.

Figure 9 is a detail cross section taken on the line 9—9 of Fig. 2.

In carrying out the invention the table generally designated 1 comprises the table top 2, a flange 3 which is continuous and depends from all four sides of the top, and a set of legs 4. Each 20 of these legs is hinged at 5. According to the present showing the uppermost leaves 6 of these hinges are secured to fillers 7 which are attached to the underside of the top 2 (Fig. 6). However, it is to be understood that the use of these 25 fillers may not always be essential and that it is entirely within the province of the invention to connect the leaves 6 directly to the top 2.

It will be seen in Figures 1 and 5 that the various hinges 5 are stationed in positions differing by 90 degrees from each other when tracing them around the outline of the table. This arrangement is necessary to enable the legs 4 to swing into closed and open position without interfering with each other, particularly to assume the neatly nested positions when closed (Fig. 5).

In order to add to the security of the flange 3, the inside corners are braced by angle irons 8. The hinged ends of the legs 4 are notched at 9 40 to seat over the angle irons when in the open positions (Fig. 1). This notching of the legs is intended to show that the legs are tightly positioned in the corners when open, and it is one of the purposes of the leg-opening mechanism to 45 jam the legs in these corners so as to insure as nearly as perfect rigidity as can be obtained with a construction of this kind.

The foregoing leg-opening mechanism is generally designated 10. The term is adapted as a 50 matter of convenience. Its function is not solely to cause the opening of the legs, but also to cause their closing. The opening and closing operations are accomplished simultaneously respecting all of the legs. Each leg has a link 11 connected 55

to it by a hinge 12. The leaf 13 of this hinge (Fig. 3) is firmly secured to the link 11 but the leaf 14 is turnably secured at 15 to the adjacent leg 4. The manner in which the turning is accomplished is immaterial, the important thing to be borne in mind being that as the link 11 exerts opening or closing pressure to swing the leg upon its hinge, there must be the provision for turning at the hinge 12, inasmuch as the link 11 does not depart from its horizontal position shown.

At their opposite ends the links 11 have hinge connections 16 with the terminal heads 17 of a central spider 18. The leaves of the hinges 16 are rigidly attached to the respective links and terminal heads, preventing any tendency toward undesired relative turning. The spider resembles the spokes of a wheel which radiate from a hub 19.

20 This hub, in fact the entire spider, is supported by a hinge coupling 20 (Fig. 2) which depends from the underside of the top 2. Inasmuch as the top 2 is rather frail, the present embodiment of the invention being in a card table, said top is desirably fortified by a plate 21 which is independently secured to the top 2 by enough screws 22 or their equivalents to provide a firm foundation. It is from this plate foundation that the coupling 20 depends and the latter is carefully located in the center of the top 2 so that the turning motion of the leg-opening mechanism will produce absolutely uniform responses in each of the legs.

35 A knuckle plate 23 (Fig. 8) is affixed to the foundation plate 21 for example by welding. A corresponding knuckle plate 24 is swiveled to the hub 19 by means of a pendant two-diameter stud 25, the large part of which is turnably fitted in a hole 26 in the hub, the small part receiving 40 a washer 27 which is followed by a nut 28 that is screwed on its threaded end.

The knuckle plates 23, 24 are joined by hinged-45ly connected leaves 29, the entire assemblage (Fig. 8) constituting the previously mentioned hinge coupling. So far it can be seen that the hinge coupling sets in a fixed position relative to the table top 2. Of course the leaves 29 swing in accordance with the opening (Fig. 2) and closing (Fig. 6) operations, but they do not depart from their relatively fixed position, the necessary turning of the central spider 18 being confined to the swivel 25, 26.

When the legs are moved to the open position (Fig. 1) it is necessary to hold them against the 55 possibility of collapsing to the closed position, and this is accomplished by a locking bar 30. This consists of the two elements 31, 32, which are hinged together at 33 (Fig. 5) and hinged at their extremities to an adjacent link 11 and to 60 an arm of the spider 18, as at 34, 35. The hinge 33 is a spring hinge, the spring 36 (Fig. 4) of which is strong enough to perpetually tend to open the elements 31, 32, in other words, to straighten the locking bar out (Fig. 1).

65 But when the locking bar is moved to the so-called straightened position it is actually slightly out of line so as to avoid the possibility of the bar being readily broken. For this purpose the abuttable ends 37 (Fig. 5) are cut off at less than 70 a right angle. There is a resulting pitch of the adjacent surfaces of the elements 31, 32 below the line 38 (Fig. 5) which would otherwise represent said surfaces if the locking bar were actually straight.

75 In addition to the spider 18 serving as the main

actuator of the leg-opening mechanism it also provides the support of a tray which in this instance is made in the form of a meshed wire plate 39 (Fig. 1), the ends of the wire being crimped around or otherwise attached to a binding hoop 40 which, in turn, is secured beneath the spider. The spokes of the spider therefore serve as dividers of the tray, partitioning the places allotted to the players around the table. A plain hoop 41 is attached on top of the spider, said hoop providing a guard which will aid in preventing knocking off glasses or packages that have been laid upon the tray 39. A pivoted cleat 42 is adapted to be moved into position (dotted lines) across a portion of the spider to hold the mechanism 10 in its closed position.

The operation is readily understood. When the table is closed all of the various parts are housed approximately as shown in Fig. 6. At this point it is desired to explain that most of 20 the leg-opening mechanism 10 is constructed of either tubular or channel metal. The legs 4, links 11 and elements 31, 32 are tubular while the spider 18 is of channel construction. This makes for lightness and strength, but the statement of this particular material is not to be considered a limitation because the table and its various parts can be constructed of any desired material.

Now reverting to the operation. The cleat 42 (Fig. 5) can be moved to the full line position prior to lifting the table preparatory to opening the legs. The latter are held in place by bringing the fingers of the hands under the legs on opposite sides. When the fingers of these hands are moved away and the table is held in the horizontal position preparatory to being set up, the entire leg-opening mechanism 10 will drop from the nested position in Fig. 6 to the extended position in Fig. 2. Thus it is a gravity operation 30 which causes the opening of the legs 4. These swing on their hinges 5 and as they do the spider 35 18 makes a partial turn on the central axis represented by the stud 25. This action can be readily understood from Fig. 5. As the central 40 spider 18 drops it makes a turn in the direction of arrow a. The extent of the turn is approximately 45 degrees, any one arm of the spider moving from the full line to the dotted line position. During this turn the link 11 (referring to 45 only one) moves in the direction of arrow b, and by tracing the direction of this arrow it will be seen that the hinge 12 turns on its pivot 15 while moving the leg 4 from the nested full line position to the dotted line position at the 50 end of the arrow c.

The previously closed locking bar 30 (full lines) is moved to open dotted line position, the hinge 33 following arrow d, and when said position is reached the natural tendency of the spring 36 60 (Fig. 4) holds the locking bar so that it will not move backward unless pulled upon preparatory to reclosing.

In this operation the previously nested tray 65 39 is let down to the accessible position shown in Fig. 2. The players seated around the table can reach under and set glasses, packages and the like upon the tray and out of the way. It is also during this operation that the hinge coupling 20 opens full as in Fig. 2. The leaves 29 remain 70 angled so as not to obstruct the later closing movement. All turning of the spider 18 occurs on the stud 25, there being no bodily turning of the hinge coupling at all.

I claim:

1. A table comprising a substantially square top, legs which have hinges connecting them to the approximate corners of the top, a coupling which includes a foundation plate that is affixed to the top in a centralized position, said coupling including hinged leaves which have common connection with a central stud, a leg-opening mechanism comprising a central spider which is turnably mounted on the stud, links interposed between the arms of the spider and adjacent legs, hinges connecting the links to said arms, and hinges connecting the links to the legs, those leaves of the latter hinges which touch the legs having turnable connections thereto.
- 5 2. A table comprising a top, a set of legs respectively located at equi-distantly located places and having hinges which connect them to the top, a coupling depending from the top in a centralized position in respect to the hinges, said 10 coupling being constructed to open and close and including a stud which moves away from and toward the top in the opening and closing movements, a spider journaled on the stud so that it can turn, links which have articulated connections at their ends with the arms of the spider and with the legs so that the legs swing to open and closed positions in correspondence with said coupling and with the turning of the spider, and a locking bar which has two elements having their remote ends hinged to one of the links and one of the spider arms, the inner ends of said elements being connected by a hinge which has a spring tending to lock the bar to an open and 15 bracing position.
3. A table comprising a top, a set of legs which have hinges connected to the top at equi-distantly spaced points and to enable the legs to be swung to open and closed positions in reference to the top, leg-opening mechanism which is operable to open and close the legs, said mechanism including a turnable spider, links hinged at their ends to the spider and to the legs to extend the legs upon turning the spider, and a tray attached to the underside of said spider utilizing the spokes of the spider as dividers of the tray.
